UNITED STATES PATENT OFFICE.

CHARLES D. HILL, OF EVANSVILLE, INDIANA, ASSIGNOR TO GOODELL & HILL, A COPARTNERSHIP COMPOSED OF HIMSELF AND LEWIS W. GOODELL, OF BEARDSTOWN, ILLINOIS.

PIPE-STEM.

1,081,929.

Specification of Letters Patent.

Patented Dec. 16, 1913.

Application filed February 3, 1913. Serial No. 745,799.

To all whom it may concern:

Be it known that I, CHARLES D. HILL, a citizen of the United States, residing at Evansville, in the county of Vanderburgh 5 and State of Indiana, have invented a new and useful Pipe-Stem, of which the following is a specification.

It is the object of my invention to provide a pipe or cigar holder with a cheap and efficient means, easily removable and replaceable, for purifying smoke. In attaining this object, I insert in the pipe stem or cigar holder, a removable cartridge composed of a plurality of longitudinal strips, preferably of bibulous material, some intersecting others transversely to form a plurality of passages, the strips being suitably notched so that the smoke may pass through these passages in succession. These strips are incased in a suitable covering, also preferably of bibulous material, and are provided with end pieces suitably notched to allow the entry and exit of the smoke from the cartridge.

25 The accompanying drawing illustrates my invention.

Figure 1 is a vertical longitudinal section through a pipe embodying my invention; Fig. 2 is a perspective view of the cartridge, 30 with the cover and one end piece removed and one of the strips partly broken away; Fig. 3 is a perspective section taken on the central, vertical, longitudinal plane of Fig. 2; Fig. 4 is a view of the complete cartridge, 35 with one end plate removed; and Figs. 5, 6, and 7 are perspective detail views of one of the end pieces and one of each of the two kinds of longitudinal pieces forming the cartridge.

40 The cartridge is composed of a plurality of longitudinal strips 10 and longitudinal strips 11 arranged at right angles to and intersecting each other, two identical end pieces 12, and a cover or casing 13. These pieces are all preferably formed of bibulous paper or cardboard. In the arrangement 45 illustrated, there are two each of the pieces 10 and 11, which are illustrated in Figs. 6 and 7 respectively. The end pieces 12 of 50 which one is illustrated in Fig. 5, each comprise a disk having two parallel slots 14 spaced from each other and from the edge of the disk, and a notch 15 near the end of one of the slots 14 but spaced slightly to one 55 side of said slot. Each longitudinal piece is

provided with a tenon 16 at each end, for fitting into one of the slots 14, with two parallel longitudinal slots 17, spaced from each other and extending the full length of the piece 10 except the tenons 16, and with 60 a notch 18 in and near the end of one of its longitudinal edges. Each piece 11 is of the same length as the piece 10 minus the tenons of the latter, and is provided with a notch 19 in each longitudinal edge and with a hole 65 20 substantially midway between the two notches 19, said two notches 19 and the hole 20 all being near the same end of the piece.

In assembling the cartridge, the two pieces 10 are turned end for end and upside down, 70 so that the notches will be near opposite corners, then the two pieces 11, turned relatively end for end, are inserted through the slots 17 of the two pieces 10, each piece 11 passing through a slot 17 in both pieces 10, 75 then the two end pieces 12, turned 180° relatively to each other, are placed at the ends of the strips 10 and 11 so that the tenons 16 pass through the slots 14, and then the cover or casing 13 is placed around the whole. 80 The cartridge thus formed provides 9 passages, *a*, *b*, *c*, *d*, *e*, *f*, *g*, *h*, and *i*, through which, by reason of the aforesaid notches and holes, smoke may pass in the order named.

85 The cartridge in its entirety may be mounted in a tube 21, conveniently of metal, which may be a skeleton tube and has projecting end portions beyond the ends of the cartridge to receive the end 22 of the stem 90 23 of the pipe bowl or cigar holder 24, and the end of the mouth-piece 26.

In operation, the smoke from the burning tobacco in the pipe bowl 24 or of the burning cigar passes along the central aperture 95 of the stem 23 until it strikes the end-piece 12 of the cartridge. It now passes through the notch 15 in such end-piece 12, along the passage *a*, through a notch 19, along the passage *b*, through another notch 19, along 100 the passage *c*, through a notch 18, along the passage *d*, through a hole 20, along the passage *e*, through the other hole 20, along the passage *f*, through the other notch 18, along the passage *g*, through a third notch 19, along 105 the passage *h*, through the fourth and last notch 19, along the passage *i*, and through the notch 15 in the other end-piece 12 to the central aperture in the mouth-piece 26. In its tortuous passage through 110

the cartridge, the smoke is purified by the removal, by the bibulous material of the cartridge, of the nicotin and other deleterious substances. When the cartridge has absorbed so much nicotin that it begins to act less efficiently as an absorbent, the mouth-piece 26 and bowl 24 and the stem 23 may be removed from the tube 21, and a new cartridge substituted in such tube for the used one. On account of the cheapness of these cartridges, such a substitution may be made very frequently.

I claim as my invention:

1. A cartridge for smoke purification in pipes and cigar holders, comprising a plurality of spaced longitudinal strips of bibulous material, said strips having tenons at their ends and being provided with a plurality of longitudinal slots, a plurality of spaced longitudinal strips of bibulous material transverse to the first-named strips and each extending through longitudinal slots in said first-named strips, end-plates located at the ends of the longitudinal strips and provided with slots into which said tenons fit, and a cover inclosing the whole, said longitudinal strips being notched to furnish a path extending successively through the different channels formed between the strips and said end-plates being notched to admit smoke into the first and allow it to pass out of the last of said passages.

2. A cartridge for smoke purification in pipes and cigar holders, comprising a plurality of spaced longitudinal strips provided with a plurality of longitudinal slots, a plurality of spaced longitudinal strips transverse to the first-named strips, end-plates located at the ends of the longitudinal strips and a cover inclosing the whole, said longitudinal strips being notched to furnish a path extending successively through the different channels formed between the strips and said end-plates being notched to admit smoke into the first and allow it to pass out of the last of said passages.

3. A cartridge for smoke purification in pipes and cigar holders, comprising a plurality of spaced longitudinal strips having tenons at their ends and provided with a plurality of longitudinal slots, a plurality of spaced longitudinal strips transverse to the first-named strips and each extending through longitudinal slots in said first-named strips, end-plates located at the ends of the longitudinal strips and provided with slots into which said tenons fit, and a cover inclosing the whole, said longitudinal strips being notched to furnish a path extending successively through the different channels formed between the strips.

4. A cartridge for smoke purification in pipes and cigar holders, comprising a plu-

rality of spaced longitudinal strips of bibulous material, said strips being provided with a plurality of longitudinal slots, a plurality of spaced longitudinal strips of bibulous material transverse to the first-named strips and each extending through longitudinal slots in said first-named strips, end-plates located at the ends of the longitudinal strips and a cover inclosing the whole, said longitudinal strips being notched to furnish a path extending successively through the different channels formed between the strips.

5. A cartridge for smoke purification in pipes and cigar holders, comprising a plurality of spaced longitudinal strips provided with a plurality of longitudinal slots, a plurality of spaced longitudinal strips transverse to the first-named strips and each extending through longitudinal slots in said first-named strips, end-plates located at the ends of the longitudinal strips and a cover inclosing the whole, said longitudinal strips being notched to furnish a path extending successively through the different channels formed between the strips.

6. A cartridge for smoke purification in pipes and cigar holders, comprising a pair of substantially parallel longitudinal strips of bibulous material provided with tenons at their ends and each having a pair of longitudinal slots, each of said strips being notched on a longitudinal edge near the corner diagonally opposite that at which the other strip is similarly notched, a second pair of longitudinal strips of bibulous material transversely intersecting the first strips, each of said second strips projecting through longitudinal slots in both of the first strips and being provided near the end opposite the similarly provided end of the other strip with a substantially central hole and with a notch in each longitudinal edge, a pair of end-pieces located at the ends of the longitudinal strips and provided with slots which receive the tenons of the first pair of strips, each of said end-pieces being notched at a point substantially diametrically opposite that at which the other end-piece is similarly notched, and a cover inclosing the whole.

7. A cartridge for smoke purification in pipes and cigar holders, comprising a pair of substantially parallel longitudinal strips each having a pair of longitudinal slots, each of said strips being notched on a longitudinal edge near the corner diagonally opposite that at which the other strip is similarly notched, a second pair of longitudinal strips transversely intersecting the first strips, each of said second strips projecting through longitudinal slots in both of the first strips and being provided near the end opposite the similarly provided end of the other strip with a substantially central hole and with a notch in each longitudinal edge, a pair of end-pieces located at the ends of the longitudinal strips and provided with slots which receive the tenons of the first pair of strips, each of said end-pieces being notched at a point substantially diametrically opposite that at which the other end-piece is similarly notched, and a cover inclosing the whole.

a notch in each longitudinal edge, a pair of end-pieces located at the ends of the longitudinal strips, each of said end-pieces being notched at a point substantially diametrically opposite that at which the other end-piece is similarly notched, and a cover in closing the whole.

8. A cartridge for smoke purification in pipes and cigar holders, comprising a pair of substantially parallel longitudinal strips provided with tenons at their ends and each having a pair of longitudinal slots, each of said strips being notched on a longitudinal edge near the corner diagonally opposite that at which the other strip is similarly notched, a second pair of longitudinal strips transversely intersecting the first strips, each of said second strips projecting through longitudinal slots in both of the first strips and being provided near the end opposite the similarly provided end of the other strip with a substantially central hole and with a notch in each longitudinal edge, a pair of end-pieces located at the ends of the longitudinal strips and provided with slots which receive the tenons of the first pair of strips.

9. A cartridge for smoke purification in pipes and cigar holders, comprising a pair of substantially parallel longitudinal strips of bibulous material each having a pair of longitudinal slots, each of said strips being notched on a longitudinal edge near the corner diagonally opposite that at which the other strip is similarly notched, a second pair of longitudinal strips of bibulous ma-

terial transversely intersecting the first strips, each of said second strips projecting through longitudinal slots in both of the first strips and being provided near the end opposite the similarly provided end of the other strip with a substantially central hole and with a notch in each longitudinal edge, and a pair of end-pieces located at the ends of the longitudinal strips.

10. A cartridge for smoke purification in pipes and cigar holders, comprising a pair of substantially parallel longitudinal strips each having a pair of longitudinal slots, each of said strips being notched on a longitudinal edge near the corner diagonally opposite that at which the other strip is similarly notched, a second pair of longitudinal strips transversely intersecting the first strips, each of said second strips projecting through longitudinal slots in both of the first strips and being provided near the end opposite the similarly provided end of the other strip with a substantially central hole and with a notch in each longitudinal edge, and a pair of end-pieces located at the ends of the longitudinal strips.

In witness whereof, I have hereunto set my hand at Evansville, Indiana, this 28th day of Jan., A. D. one thousand nine hundred and thirteen.

CHARLES D. HILL.
